UNITED STATES PATENT OFFICE.

GEORGE HAGEN, OF ZUMBROTA, MINNESOTA.

POWER-DRIVEN RASP.

1,116,058.

Specification of Letters Patent.

Patented Nov. 3, 1914.

Application filed July 2, 1913. Serial No. 777,014.

To all whom it may concern:

Be it known that I, GEORGE HAGEN, a citizen of the United States, residing at Zumbrota, in the county of Goodhue, State 5 of Minnesota, have invented certain new and useful Improvements in Power-Driven Rasps; and I do hereby declare the following to be a full, clear, and exact description of the invention, such as will enable others 10 skilled in the art to which it appertains to make and use the same.

This invention relates to new and useful improvements in power driven rasps and has particular reference to the provision of a 15 rasp for use in farriery.

The object of the invention resides in the provision of a rasp of the class described, which shall be efficient in use and which shall be so constructed as to permit of ready 20 and economical manufacture.

With this and other objects in view, the invention resides in the novel combination, formation and arrangement of parts to be more fully hereinafter described and illustrated in the accompanying drawings and particularly pointed out in the claim hereto appended.

Reference is had to the accompanying drawings wherein similar characters of reference designate corresponding parts throughout the several views, and in which:

Figure 1 is a side elevational view of a preferred form of the rasp, Fig. 2 is a vertical longitudinal sectional view of the device, Fig. 3 is a sectional view on the line 3—3 of Fig. 1, Fig. 4 is a transverse sectional view on the line 4—4 of Fig. 1, Fig. 5 is an end view of the rasp and Fig. 6 is a perspective view of the body block.

Referring more particularly to the drawings, the rasp is shown as comprising a body block 5 which is substantially rectangular in end elevation and which has two opposed side faces outwardly bowed. It is oval in 45 cross section and may have imparted to it a rocking motion about its longitudinal axis 18' to produce a greater or less cutting action as the work may demand. The block is provided in its other side faces with elongated recesses 6 which are substantially semi-circular in cross section and which terminate short of the ends of the block, to receive the cylindrical rasp members 7 and 8. These rasp members comprise cylindrical

body portions which are provided at their 55 ends with beveled edges for receiving the cone-shaped securing members 9 and 10 which are positioned on a shaft 11 journaled as at 12 in the ends of the block. The cone-shaped member 9 is keyed to the shaft and 60 is provided on its periphery with a socket 13 for receiving a projection 14 carried by the beveled edge of a rasp member. The cone-shaped member 10 has threaded engagement on the other end of the shaft. It will be 65 observed that by the position of the cone-shaped members, the rasp cylinders may be securely clamped with relation to the shafts 11. As is shown in the drawings, the rasp 7 is formed with coarse teeth on its periphery 70 and the rasp 8 with finer teeth for finishing. Suitable bearing members 15 are provided on the ends of the block and secured thereto as at 16 to hold the ends of the shaft in relation to the block.

To provide means for imparting rotary motion to the shafts 11, the said shafts are extended past the inner end of the block and provided with gear wheels 17 keyed thereon to mesh with a gear 18 carried by a 80 shaft rotatable in the handle portion 19 of the device. This handle portion includes an enlarged head cutaway as at 20 to receive the afore-mentioned gear wheels. To secure the handle portion to the block a plurality of 85 pins 21 are provided which seat in sockets provided therefor in the head of the handle portion and securing screws 22 are passed through the head of the handle portion and the adjacent end of the block. The shaft 90 18' extends through a bore 23 formed in the handle portion and is operatively connected at the outer end of the handle portion to a conventional type of flexible power shaft 24.

To provide means for hanging the device up when not in use the outer end of the block is provided with a reduced extension 25 which is apertured as at 26.

In operation, the bowed portion of the 100 block is used as a rest and the angle at which said bowed portion is positioned to the object operated upon determines the depth to which the rasp teeth cut. It will be seen that by this construction and arrangement 105 that a steady operation is procured. By the provision of the fine and coarse tooth rasp members it will be seen that the roughing

and finishing may be done with only one tool and without cutting off the power.

What is claimed is:

In a device of the class described, a head portion oval in cross section, the opposed side faces thereof provided with concaved recesses terminating short of the ends thereof, cylindrical rasp members rotatably

mounted in said recesses, and means for rotating said rasp members.

In testimony whereof, I affix my signature, in the presence of two witnesses.

GEORGE HAGEN.

Witnesses:

H. E. WEISS,
LARS A. HOLTAN.
